COMBINED KITCHEN RANGE HOOD AND RACK

Kenneth E. Rawald, Anaheim, Calif., assignor to Norris-Thermador Corporation, Los Angeles, Calif., a corporation of California

Filed Aug. 29, 1966, Ser. No. 3,644

Term of patent 14 years

(Cl. D81—25)

FIG. 1 is a perspective view of a combined kitchen range hood and rack taken from one side thereof, showing my new design, the racks being shown in open and closed condition,

FIG. 2 is a perspective view thereof taken from the front thereof,

FIG. 3 is a side elevation view thereof,

FIG. 4 is a top plan view thereof, and

FIG. 5 is a bottom plan view thereof.

The side of the hood not shown is the same as the side shown in FIG. 3 while the undisclosed back surfaces of the hood are plain.

I claim:

The ornamental design for a combined kitchen range hood and rack, as shown and described.
